UNITED STATES PATENT OFFICE

NICHOLAS H. STUART, OF BUFFALO, NEW YORK, ASSIGNOR TO REMINGTON RAND INC.,
OF BUFFALO, NEW YORK

LOOSE-LEAF BINDER

Application filed March 13, 1929. Serial No. 346,593.

The invention relates to temporary binders and it has particular relation to binders of the loose leaf type in which the cover members may be adjusted toward and away from one another in order to clamp groups of pages of varying members therebetween or to permit of the quick removal of the pages therefrom or the insertion of additional pages therein.

10 One of the objects of the present invention is to provide a simple and efficient mechanism for clamping a stack of pages between the covers of a binder and which embodies a single member operable with one hand for both releasing the covers from clamped position and for moving them relative to each other in order to permit of the quick and easy insertion or removal of pages from the binder.

20 Another object of the invention is to provide a novel locking mechanism for a binder of the character described which is simple in construction and arrangement and which may be assembled and disassembled with a minimum of time and effort.

Other objects of the invention will appear from the following specification and appended claims.

In the accompanying drawing,

30 Fig. 1 is a plan view of a loose leaf binder with the covers thereof in an open position and with portions broken away to more clearly illustrate the improved adjusting and locking mechanism.

35 Fig. 2 is an enlarged sectional view of a portion of the binder taken on line 2—2 of Fig. 1.

Fig. 3 is an enlarged fragmentary plan view of the improved locking mechanism.

40 Fig. 4 is a transverse sectional view taken on line 4—4 of Fig. 3.

Referring to the drawing, a binder constructed in accordance with the present invention is shown as comprising a pair of cover members 1 and 2 each of which includes a rectangular frame 3 having sheet metal plates 4 and 5 secured to the inner and outer sides thereof by rivets 6. Channel members 7 are secured to the adjacent edges of the cover members 1 and 2 respectively and are

formed with ear portions 8, (Fig. 2), which are pivotally connected to ears 9 provided on each of a pair of clamping bars 10. These bars are provided with apertures 11 adapted to receive the ends of a pair of studs 12 which are carried by a pair of transfer bars 13. The transfer bars 13 directly engage the opposite sides of a group of pages 14 and are each provided with a pair of posts 12' which extend in opposite directions through a series of registering perforations 15 formed in the pages.

An adjusting bar 17 extends across the cover 1 between the plates 4 and 5 and is provided with a plate member 18 formed with a central offset portion 18' to provide a guide-way for slidably receiving a ratchet bar 19 which is secured to the cover 1 between the plates 4 and 5. The opposite ends of this plate member 18 are suitably secured to the bar 17. A pair of flexible straps or thongs 20 are each secured at one end to the adjusting bar 17 by a clip 21 (Fig. 1), and extend through the channel members 8 and through slots 22 provided in the transfer bars 13 and are fixed at their other ends in the channel members 8 carried by the cover member 2. The stack or group of pages 14 is preferably notched transversely as indicated at 23, (Fig. 2), in order to receive the thongs 20 where they cross from cover to cover back of the pages.

The adjusted bar 17 is locked in adjusting position in order to maintain the clamping bars 10 together by means of a pawl 24 which is pivotally mounted as at 25 upon the bar 17 and which is yieldably urged into engagement with the rack bar 19 by means of a spring 26. A plate 27 is fixed to the pawl 24 by means of a rivet or the like 27' and is formed with a projection or finger 28 which projects into a slot or recess 29 formed in the offset portion 18' of plate member 18, and overlies the rack bar 19 for engagement by a pin 30. This slot 29 in plate 18 extends through one end of the plate as indicated at 29' to accommodate the pawl 24. This pin extends transversely through a stud or rotatable member 31 which is rotatably mounted in the bar 17 and extends through an opening in plate 18 and is

provided with an annular shoulder or collar 32, (Fig. 4), to prevent the upward displacement thereof. The stud 31 is slotted as at 33 to receive a handle 34 which is pivotally mounted on the pin 30 and which extends through a slot 35, (Fig. 1), formed in the plate 4 of the cover. The handle 34 is provided with a shoulder 36 for engagement with the stud to arrest the upward or outward 10 swinging movement of the handle 34 in a position substantially perpendicular to the plane of the cover. A leaf spring 37 bears against the lower extremities of the handle 34 and tends to normally maintain the handle in an inoperative position flat against the cover. 15

When it is desired to release the covers to permit of the insertion of pages in the binder or the removal of pages therefrom, the handle 34 is first swung upwardly about the pin 30 against the action of the spring 36 to the position shown in Fig. 4. The handle is then turned about an axis substantially normal to the plane of the cover thus causing the pin 30 to bear against the finger 28 of the plate 27 and release the ratchet 24 from engagement with the rack 19 against the action of the spring 26. As soon as the ratchet is released from the rack bar 19 the handle 34 may be employed to move the adjusting bar 17 and the parts carried thereby longitudinally of the rack bar 19 in order to release the group of pages from the binder or to clamp it more firmly between the cover members. It will be noted that the shoulder 36 on the handle 34 forms with the stud 31 a solid abutment thus permitting considerable force to be exerted on the handle in tightening the adjusting bar and thongs in an adjusted position. 35

From the foregoing it will be apparent 40 that a very simple and efficient mechanism is provided and in which the parts may be quickly assembled and disassembled. For example, the pin 30 performs the triple function of serving as a lever to operate the pawl, 45 maintaining the stud 31 against displacement from the plane of the bar 17 and providing a pivotal bearing for the handle 34, thus permitting of quick assembly or disassembly of parts.

50 The invention may be modified in construction and arrangement without departing from the spirit and scope of the invention as defined in the appended claims.

What is claimed is:

55 1. In a temporary binder the combination of a pair of cover members, a rack mounted on one of said cover members, an adjusting bar mounted for movement longitudinally of said rack, leaf-holding means connecting said adjusting bar and the other of said covers, a pawl pivotally mounted on said adjusting bar for engagement with said rack, and means 60 mounted on said adjusting bar for pivotal movement for releasing said pawl from engagement with said rack including a handle

portion foldable against said cover when said means is not in use.

2. In a temporary binder the combination of a pair of cover members, a rack mounted on one of said cover members, an adjusting bar slidably mounted on said rack for adjustment longitudinally thereof, leaf-holding means connecting said bar to the other of said cover members, a pawl mounted on said adjusting bar for pivotal movement about an axis normal to the plane of said bar for engagement with said rack, a rotatable member mounted on said bar for rotation about an axis parallel to the axis of movement of said pawl for releasing said pawl from engagement with said rack, and a handle mounted on said rotatable member for pivotal movement about an axis transverse to that of the movement thereof and adapted to actuate said rotatable member, and for moving said adjusting bar relative to said rack. 70 75 80 85

3. In a temporary binder the combination of a pair of cover members, a rack mounted on one of said cover members, an adjusting bar slidably mounted on said rack for adjustment longitudinally thereof, leaf-holding means connecting said bar to the other of said cover members, a pawl mounted on said adjusting bar for pivotal movement about an axis normal to the plane of said bar for engagement with said rack, a rotatable member mounted on said bar for rotation about an axis parallel to the axis of movement of said pawl for releasing said pawl from engagement with said rack, and a handle mounted on said rotatable member for pivotal movement about an axis transverse to that of the movement thereof between an inoperative position parallel to the plane of said cover, and an operative position substantially perpendicular thereto and adapted to be rotated to release said pawl from engagement with said rack and to be employed as a means for moving said bar and pawl longitudinally of said rack. 90 95 100 105 110

4. In a temporary binder the combination of a pair of cover members, a rack mounted on one of said cover members, an adjusting bar slidably mounted on said rack for adjustment longitudinally thereof, a plurality of thongs connecting said bar to the other of said cover members, a pawl mounted on said adjusting bar for pivotal movement about an axis normal to the plane of said bar for engagement with said rack, a rotatable member mounted on said bar for pivotal movement about an axis parallel to the axis of movement of said pawl for releasing said pawl from engagement with said rack, a handle mounted on said rotatable member for pivotal movement about an axis transverse to the axis of rotation of said rotatable member between an inoperative position substantially parallel to the cover and an operative position substantially per- 115 120 125 130

pendicular thereto, and a spring for yieldably maintaining said handle in its inoperative position.

5. In a temporary binder the combination of a pair of cover members, a rack mounted on one of said cover members, an adjusting bar slidably mounted on said rack for adjustment longitudinally thereof, a plurality of thongs connecting said bar with the other of said cover members, a pawl mounted on said adjusting bar for pivotal movement about an axis normal to the plane of said bar for engagement with said rack, a rotatable member mounted on said bar for pivotal movement about an axis parallel to the axis of movement of said pawl for releasing said pawl from engagement with said rack, a handle mounted on said rotatable member for pivotal movement about an axis transverse to the axis of rotation of said rotatable member between an inoperative position parallel to the plane of said cover, and an operative position substantially perpendicular thereto and adapted to be rotated to release said pawl from engagement with said rack and employed as a means for moving said bar and pawl longitudinally of said rack, and a stop for arresting the pivotal movement of said handle in its operative position.

6. In a temporary binder the combination of a pair of cover members, a rack mounted on one of said cover members, an adjusting bar mounted on said rack for movement longitudinally thereof, means connecting said adjusting bar with the other of said cover members, a pawl carried by said adjusting bar for engagement with said rack, a stud rotatably mounted in said adjusting bar adjacent to said pawl, a pin carried by said stud for engagement with said pawl and for maintaining said bearing member against displacement from said adjusting bar, and a handle pivotally mounted on said pin for swinging movement between an inoperative position substantially parallel with said adjusting bar and an operative position substantially perpendicular thereto, said handle being adapted when in an operative position to be turned to swing said pin to disengage said pawl from said rack and by means of which handle said adjusting bar may be moved longitudinally of said rack.

7. In a temporary binder the combination of a pair of cover members, a rack mounted on one of said cover members, an adjusting bar mounted on said rack for movement longitudinally thereof, means connecting said adjusting bar with the other of said cover members, a spring actuated pawl carried by said adjusting bar for engagement with said rack and having an extension provided thereon, a stud rotatably mounted in said adjusting bar adjacent to said pawl, a pin carried by said stud for engagement with said ex-

tension and for maintaining said bearing member against displacement from said adjusting bar, a handle pivotally mounted on said pin for swinging movement between an inoperative position substantially parallel with said adjusting bar and an operative position substantially perpendicular thereto, said handle being adapted when in an operative position to be turned to swing said pin to disengage said pawl from said rack and by means of which handle said adjusting bar may be moved longitudinally of said rack, and a spring for yieldably maintaining said handle in an inoperative position.
